DEVICE FOR RESILIENTLY POSITIONING
DEMOUNTABLE BODIES

Ragnar A. Norbom, Clifton, N. J., assignor to
Motor Terminals Company, New York, N. Y., a
corporation of Delaware

Application August 22, 1934, Serial No. 740,973

20 Claims. (Cl. 105—366)

This invention relates to demountable truck bodies or freight containers adapted to be carried interchangeably on a highway truck or trailer and another vehicle, especially a railway car. In the inter-city transportation of package freight, it has been found very efficient to load the freight into demountable bodies, after which such loaded bodies are placed on a highway truck or trailer, transported to a rail head, lifted and deposited on suitable anchorages on a railway car. The loaded body is then transported by the railway car to another city, and then transferred to a highway truck or trailer for ultimate delivery.

In the operation of railway cars, there are longitudinal buffing and tugging strains which tend to shift the load in the bodies or bodies themselves longitudinally, and may at times become so severe as to cause injury to the contents or to the body, by reason of the inertia impact of the load against the body ends, and may even tear the body loose from the anchorages. To obviate this difficulty it has been proposed to mount the anchorage of the railway car or the body in such manner that it may shift longitudinally, and to oppose such shifting by coiled compression springs on opposite sides of the anchorage.

It is an object of my invention to simplify the yielding anchorage arrangement and reduce the initial cost thereof. It is a further object of the invention to introduce an element of friction in addition to the resilient resistance to movement, with the result that the body is more firmly held against trembling or shifting for small shocks, but at the same time may yield when necessary.

The anchorages preferably comprise coacting projections and sockets, one member of which is carried by the vehicle and the other by the body. Now in accomplishing the above objects, I form the socket member by leaf springs held at their ends and bowed apart intermediately to provide an opening adapted to receive the projection carried by the other member of the combination. The result is that these springs at once form the socket and the resilient resistant and operate to insure an effective positioning of the body on the vehicle and as a self-centering device for a body not accurately located, and then will yield longitudinally in case of severe blows. The weight of the body being supported by engagement of its sill on the vehicle, there results friction between the body and the vehicle tending to prevent movement, and this friction may be augmented by friction between the spring socket and a rub plate, which may conveniently form the base for carrying the projection.

I prefer to carry my spring socket members by the body in which case they are mounted within the floor frame and beneath the floor of the demountable body, and hence, do not restrict in any manner the carrying capacity of the container or provide objectionable obstructions on the railway car, but are effective to prevent the transmission of sudden blows from the car to the body.

My invention includes the broad idea of the socket forming spring members, and more particularly the provision of a pair of leaf springs held at their ends and separated intermediately to provide a somewhat elongated but restrictive opening for the reception of the projection. The feature of carrying the projection by a rub plate which the adjacent edges of the springs may engage is also included within my invention. Other characteristics included within the invention will become apparent from the following description of a preferred embodiment illustrated in the drawings.

In the drawings Fig. 1 is a side elevation of a portion of a railway car equipped with anchoring projections and a body mounted thereon partly broken away to disclose one of the anchorages on the railway car; Fig. 2 is a bottom plan of the body; Fig. 3 is a plan of the complete anchorage device being a cross-section through the floor frame of the demountable body and showing also the projection carried by a vehicle beneath such body; Fig. 4 is a longitudinal vertical section through the demountable body and the adjacent portion of the vehicle floor, the view being alongside of the anchorage device; Fig. 5 is a detail of the means for attaching the ends of the spring socket, being a vertical cross-section, for instance on the line 5—5 on Fig. 3.

In Fig. 1, A is to be taken as indicating an ordinary railway flat car on which demountable bodies, preferably two or more, may stand in longitudinal alignment; B indicates the body itself, which may be of my standard construction having a floor frame composed of longitudinal side sills b, end sills b₁, and internal longitudinal and transverse beams, shown in Fig. 2, and some of them designated b₂. Secured to such floor frame are side walls b₃ and end walls, each of which may be equipped with double-hinged doors such as shown at b₅. The side and end walls carry a suitable roof b₇ and the body sides are provided with suitably braced load attaching hooks b₈ by which the body may be lifted for transfer from one vehicle to another. Resting on the floor frame within the body walls are suitable layers of flooring b₉. My shock absorbing anchorages are mounted

beneath such flooring and are secured by members of the floor frame as hereinafter described.

The socket anchorage of this invention, as shown in Figs. 2, 3, and 4, comprises two leaf springs 10 with their wide dimensions facing each other and with their end portions rigidly held, the intermediate portions being free and bowed outwardly to provide an open space between them which is restricted in opposite directions. More specifically, the space is bounded by four ogee curves. As shown these curves are cosinusoids developed through 360°. The spring-leaves 10 are reinforced on their outer sides by other leaves 11, which lead from their curved portions to the flat portions and these leaves 11 are shown as further reinforced by substantially straight leaves 12. All of these leaves stand on edge, that is, their width extends vertically, and their contacting end portions are attached to the body.

As shown, the contiguous spring leaves adjacent the ends are embraced by a hollow block or rectangular band 20, which is preferably made of steel shaped to size, heated and shrunk on the spring leaves. On opposite sides of the box-like member thus produced are a pair of angle clips 21, which are secured to the member and the leaves by through rivets 22.

The construction described makes a self-contained spring socket extending for considerable length, terminating at its ends in outward flanges 24 adapted to ready attachment to the body floor frame. As shown in Figs. 3 and 4, I have provided within the channel space of the end sill b1 a reversely faced channel member 26, which is secured to the end sill. The adjacent flanges 24 of the spring socket abut the web of this channel 26 and are effectively secured thereto by bolts 27 and nuts 28. At the other end, the angle flanges 24 make a similar engagement with the web of a reinforcing angle 29 bearing against one of the cross sills b2, bolts 27 and nuts 28 securing the parts together.

It will be seen that the spring socket is simply constructed and readily attached to the demountable body and may be readily replaced in case of breakage.

The projection which cooperates with the spring socket described is shown at 30 in Figs. 1, 3, and 4. Such projection is cylindrical for the most part but has a conical top 31. It is carried by an elongated plate 32, which is preferably provided with depressed seats 33 having openings for the reception of bolts 34 to secure the member to the vehicle floor. The projection may readily be made hollow, as indicated in Fig. 4, and be formed integral with the plate 32, and may, if desired, be a steel forging or a malleable casting.

With such construction as above described when the body is placed on the vehicle, the body sills rest on the vehicle floor and the main springs 10 of the socket frictionally embrace the projection 30. The lower edges of the springs may also have a frictional engagement with the rub plate 32. Due to the restrictive character of the opening 15 between the spring leaves, the cylindrical projection occupying the opening will be effective to hold the body in position laterally and longitudinally, and the frictional engagement of the body sills with the vehicle, supplemented by the frictional engagement of the springs with the cooperating member on the vehicle, will further resist movement and prevent shifting due to light blows, but the yielding character of the springs will enable the

body to shift longitudinally to take up the shock in case of abnormal buffing or tugging stress.

My peculiar spring socket is also of advantage in enabling the ready seating of the body as it is lowered into position without requiring exact registration between the socket member and projection—that is to say, if the body is longitudinally out of registration in one direction or the other a short distance, the restricted portion of the opening 15 comes over 10 the conical top of the projection and the spring leaves engaging such projection slide down on the same, due to the weight of the body, and cam the body longitudinally until the proper registration is obtained. Likewise, if the body is 15 out of registration laterally, the engagement of one or the other spring leaves with the conical top will tend to force the lower end of the spring outwardly and toe the upper edge inwardly so that a slightly conical socket is obtained which 20 effects the lateral position.

It will be seen that my spring socket, in addition to the advantage of being a shock absorber, enables the more ready placement of the body. Should the anchorages engage, with the 25 body out of exact registration, the retracting action of the spring leaves operates to center the body as soon as the buffing or tugging stresses of the vehicle, cause shifting in the proper direction.

It is to be understood that the spring anchorages shown in detail in Figs. 3 and 4 are mounted at least at four corners of the body. I prefer to employ also a pair of intermediate positioning members as indicated at 10a in Fig. 2. Such additional members are mounted between cross beams b2 of the body floor frame in the central region. These intermediate anchorages are designed to prevent any possible displacement of the body if there should be such a vertical jolt as would lift the body at one end or the other above the vehicle projection sufficiently to cause the sockets at that end to clear the projections. In case of such a jolt, anchorages at the other end would form the fulcrum 45 about which the body would rise and the centrally located anchorages would remain well in engagement to maintain the body in proper registration even though the sockets of the distant ends might clear the corresponding fixed 50 projections. This is simply a safety provision for an abnormal condition which would not often occur in railway transportation but is more liable in truck transportation; for example, if a truck wheel should drop into a man-hole in a city 55 street.

It will be understood from the description heretofore given that my shock absorbing sockets may be constructed comparatively cheaply and may be very readily put in place, thus being 60 adapted for use with bodies which are shipped in a knocked-down form. They provide effective sockets and coact with the projections and rub plates of the companion members to introduce desired friction against shifting. At the same time they allow a sufficient amount of longitudinal shifting to cause a very effective shock absorbing action. Finally, this spring leaf socket enables the more ready placement of the body in position and effects a self-centering action for an in- 65 accurately placed body.

I claim:

1. The combination of a vehicle and a demountable container adapted to be carried thereby of an anchorage device comprising a project- 75

- ing member and a socket one of which is carried by the vehicle and the other by the demountable container, said socket comprising spring leaves placed on edge and having their inner faces 5 adapted to engage the projecting member at their center portions and thereby cushion relative horizontal movement, said leaves being connected together and to their carrier only adjacent their ends.
10. 2. The combination, with a vehicle and a demountable container adapted to rest thereon, of an anchorage device comprising two members, one secured to the vehicle and the other to the base of the container, one of said members comprising a projection and the other comprising a relatively rigid portion secured to a support and a resilient socket portion formed to receive the projection and adapted to change its shape in case of horizontal movement of the projection 15 within the socket.
15. 3. The combination of a vehicle and demountable body adapted to be carried thereby, and an anchorage device having one member attached to the vehicle and the other to the body, one member of such anchorage device comprising a rigid projection and the other member comprising spring elements adapted to embrace the projection while allowing movement thereof and means to secure said spring elements in place.
20. 4. An anchorage for positioning demountable containers on vehicles comprising a projection and a pair of spring leaves bowed apart to provide a socket to receive the projection, and means spaced from said socket to secure said anchorage 25 to a support.
25. 5. An anchorage for positioning demountable containers on vehicles comprising a cylindrical projection on one member and a pair of spring leaves with their wide dimensions facing each 30 other and spread apart to provide a socket to receive the projections and means remote from said socket to attach said anchorage to a support on the other member.
30. 6. A device for anchoring a container on a vehicle comprising a projection on one of said 35 members and a socket to receive it on the other member, said socket being made of a pair of spring leaves spaced apart intermediately, said leaves approaching each other in each direction 40 beyond the projection to provide a restricted resilient space in which the projection may move and means for attaching said approaching portions 45 of the leaves to the device carrying the socket.
45. 7. A device for anchoring a container on a vehicle comprising a projection on one of said members and a socket to receive it on the other member, said socket being made of a pair of spring leaves with their sides facing each other 50 and spaced apart intermediately, said leaves approaching each other in ogee curves beyond the projection to provide a restricted resilient space in which the projection may move, said leaves being attached to said other member remote 55 from said intermediate part.
55. 8. A device for anchoring a container on a vehicle comprising a projection on one of said members and a socket to receive it on the other member, said socket being made by outwardly 60 bowed portions of a pair of spring leaves, reinforces for said leaves and attaching devices carried by said other member for the leaves and reinforced spaced from said socket.
65. 9. A device for anchoring a container to a vehicle comprising a projection adapted to be 65 secured to one of said members and a socket therefor adapted to be secured to the other member, said socket comprising a pair of spring leaves having their end portions parallel to each other and their intermediate portions bowed outwardly 70 to provide a yielding receptacle, means for clamping the end portions together, and means for attaching such end portions to the device which is to carry the socket.
70. 10. A device for anchoring a container to a vehicle comprising a projection on one of said members and a spring socket therefor on the other, said socket being made of a pair of leaf springs having their end portions parallel, their intermediate portions bowed outwardly to provide a resilient receptacle, reinforcing leaves on the outer sides of the spring leaves, and a strap secured to said other member and embracing the end portions of the spring leaves and reinforcing leaves.
75. 11. A device for anchoring a container to a vehicle comprising a projection on one of said members and a spring socket therefor on the other, said socket being made of leaf springs having their end portions parallel and their intermediate portions bowed outwardly to provide a receptacle with resilient sides, a strap embracing the end portions of the spring leaves, and angle clips secured to the embracing strap and furnishing means for attachment of the device 80 to said other member.
80. 12. The combination of a demountable body having a floor frame, leaving a space beneath the floor, a socket adapted to receive a positioning member and carried in such space and comprising a pair of spring leaves standing on edge and intermediately bowed outwardly to receive positioning means for the body, and means for attaching the end portions of the spring leaves to members in the floor frame of the body.
85. 13. The combination of a demountable body having a floor frame, leaving a space beneath the floor, a socket carried in such space and comprising a pair of spring leaves outwardly bowed away from each other to provide a resilient receptacle for a projection, reinforcing leaves on the outer side of the spring leaves and attaching devices secured to the spring leaves at their adjacent ends and to the reinforcing leaves and to members in the floor frame of the body.
90. 14. The combination of a demountable body having a floor and a floor frame with transverse beams, a spring socket secured to said beams in a space beneath the floor, said socket comprising two spring leaves intermediately spaced 95 apart and having end portions parallel with each other, reinforcing leaves engaging the spring leaves, a reinforcing strap surrounding the spring leaves and reinforcing leaves at the adjacent ends of the leaves, angle clips on the outer sides of 100 the straps, through rivets passing through the angle clips, straps and spring leaves to hold said parts together, and means for attaching the angle clips to transverse beams of the floor frame, said socket being adapted to receive positioning means 105 for said body.
100. 15. An anchorage device for a container when mounted on a vehicle comprising a plate adapted to be secured to one of such members and carrying a projection, a socket adapted to be secured to the other member to receive the projection made of a pair of spring leaves outwardly bowed apart from each other to receive the projection, the lower edges of such leaves being adapted to engage the face of said plate and 110

means adjacent the ends of the springs to secure the same to said other member.

16. An anchorage device for a demountable container when mounted on a vehicle consisting of a socket adapted to be carried by one of such members and comprising a pair of spring leaves intermediately bowed apart to provide a resilient opening adapted to receive a projection but restricted on opposite sides thereof, and a rub plate adapted to be secured to the other of such members and extending lengthwise of the spring leaves and having a face adapted to be engaged by edges of the leaves, an upstanding projection on the rub plate adapted to enter the central portion of the space between the spring leaves and means to secure the end portions of the leaves to the member having the socket.
17. The combination of a vehicle and a demountable container adapted to be carried thereby of an anchorage device comprising a projecting member and a socket, one of which is carried by the vehicle and the other by the demountable container, the projecting member having a rub plate at its base and the socket comprising spring leaves placed on edge and having inner faces adapted to engage the projection at their center portions and thereby cushion relative horizontal movement and bearing at their lower edges against the rub plate, said leaves being connected together and to their carrier at their ends only.

18. An anchorage device for connecting a de-

mountable body to a vehicle carrying the same comprising a plate adapted to be mounted on one of such members and carrying a cylindrical projection with a conical top, a socket adapted to be mounted on the other member to receive the projection made of a pair of spring leaves placed on edge with their end portions in contact and attached to such other member and their intermediate portions bowed apart from each other to provide a resilient receptacle to receive the projection, the lower edges of such leaves being adapted to bear on the plate.

19. A socket for a shock absorbing anchorage for a demountable container when mounted on a vehicle, adapted to receive a positioning member, and comprising a pair of spring leaves having their wide dimensions facing each other and their end portions parallel to each other and rigidly held together, and their intermediate portions bowed outwardly and having some freedom of movement to provide a resilient socket, each outward bow being substantially a cosinusoid developed through 360°.

20. A socket comprising a pair of cooperating spring leaves adapted to be carried by a support and intermediately bowed apart in cosinal curves to provide an opening restricted in opposite directions, said socket being adapted to yieldingly receive a projection which, with the socket, may constitute a shock absorbing anchorage between a demountable container and a vehicle.

RAGNAR A. NORBOM.
